UNITED STATES PATENT OFFICE.

OSCAR H. SCHRAM, OF OSHKOSH, WISCONSIN.

ADJUSTABLE CHAIR.

1,393,457.

Specification of Letters Patent. Patented Oct. 11, 1921.

Application filed April 26, 1920. Serial No. 376,652.

To all whom it may concern:

Be it known that I, OSCAR H. SCHRAM, a citizen of the United States, and resident of Oshkosh, in the county of Winnebago and

5 State of Wisconsin, have invented certain new and useful Improvements in Adjustable Chairs; and I do hereby declare that the following is a full, clear, and exact description thereof.

10 My invention relates to new and useful improvements in chair structures, and is more particularly directed to the provision of means for adjusting the effective height of leg members of the chair, and although 15 in the present embodiment of my invention, I show a chair of the rocking type, it will be appreciated that my invention may also be associated with any other type of chair in which it would be desired to procure this 20 adjusting function.

It is primarily the object of my invention to provide a simple, durable and otherwise commercially practicable chair structure wherein the effective height of the leg members thereof may be adjusted, and wherein particularly the seat member of the chair may be inclined downwardly toward its rear end to suit the comfort requirements of the user.

25 It is further my object to provide an adjustment of this character which may be effected in a most convenient and ready manner, and to this end it is more particularly 30 my object to provide an arrangement for counter-balancing the normal weight of the upper portion of the chair with respect to the adjustable leg members whereby the seat member may be thus adjusted with a minimum amount of effort.

35 A still further object is to embody the aforesaid features of construction in a rocker chair of the heavy upholstered type wherein the operative parts of the adjusting mechanism are housed within the structure of the chair in such manner as not to detract from the desired attractive appearance of the chair structure.

With the above and other objects and advantages in view, which will be apparent 50 as the description proceeds, my invention resides in the novel features of construction, combination and arrangement of the parts

as hereinafter described and defined by the appended claims.

In the accompanying drawings: 55
Figure 1 is a vertical sectional view through a rocker chair constructed in accordance with my invention, the plane of this section being indicated by the line 1—1 of Fig. 3.

Fig. 2 is a side elevational view of the lower portion of the frame structure of the chair.

Fig. 3 is a sectional view through the chair in a plane at right angles to the plane 65 of Fig. 1, as indicated by the line 3—3 of Fig. 1.

Fig. 4 is a horizontal sectional view through the chair on a plane indicated by the line 4—4 of Fig. 1. 70

Fig. 5 is a detail sectional view of the operating handle lever, the plane of this section being indicated by the line 5—5 of Fig. 3.

Referring now more particularly to the 75 drawings, the frame work of the chair structure constituting the present embodiment of my invention, comprises the usual front, rear and side seat box sills 5, 6 and 7 respectively. Back posts 8 are connected 80 with and extend upwardly from the rear corners of the seat box and carry the usual cross pieces 9, while arm rest posts 10 extend upwardly from the forward corners of the chair box and are connected with 85 these parts, and in completing the chair, all of these parts would be suitably cushioned and upholstered. The sills of the seat box are connected by the usual triangular brace blocks 13 set in the corners of the 90 box and suitably fixed to the sills.

By reason of the depth of the cushion seat structure in the present type of chair, the legs of the chair are relatively short, and the front legs 14 of the chair are rigidly 95 secured to arcuate rocker bars 15, the upper end portions of the legs being reduced and passed through apertures in the forward brace blocks 13, this reduction of the upper portions of the legs forming consequent shoulders 14a which substantially abut the bottom corner portions of the seat box. The reduced leg portions are slightly loose in the blocks 13 whereby they are permit-

ted slight movement in a direction longitudinally of the rocker bars, and this movement is rendered pivotal in nature by pins 16 passing through the upper portions of 5 the legs and through the side sills 7 and blocks 13.

The rear legs 17 of the chair are rigidly secured to the rear portions of the rocker bars 15 and have their upper end portions 10 reduced similarly to the front legs, the reduced portions being slideable in apertures in the rear brace blocks 13 and this reduction of the rear legs forms consequent shoulders 15 at the intermediate portions of the legs, 18 at the lower portions of the ends of the rear box sill 6 being cut away to provide clearance for such shoulders and thus permit a considerable degree of relative vertical movement between the rear legs and box 20 sill. Thus, the rear portions of the seat structure may be raised or lowered with respect to the rear legs, and such raising and lowering movement would of course procure a certain pivotal movement of the front 25 legs 14, although in practice this pivotal movement of the front legs is inconsequential. The weight of the seat and back structure of the chair is counter-balanced by contractile coil springs 19 secured to the bracket 30 arms 20 at the upper extremities of the rear legs and secured to the rear corner braces 13, which are disposed therebelow.

The rear portion of the seat structure is 35 adjustably held at any desired elevation by a pair of levers 21, intermediately pivoted to the seat structure, preferably at the inner face of the rear box sill 6, the outer end portions of these levers passing into the upper 40 portions of the rear legs 17, through wear plates 22 secured to the inner sides of said legs.

The inner ends of the levers 21 have common pivotal connection with an operating link 21^a which extends upwardly in the substantial plane of the back of the chair and which is pivotally connected with a crank arm 23 on one end of a stub shaft 24 which is journaled in a bearing bracket 25 secured to and depending from the upper cross piece 45 50 9 of the back structure. The outer end of the shaft carries an upstanding lever 26 and this handle lever is adjustably held in any desired position by a plunger bar 27 slideable through a longitudinal bore in the handle 55 and projecting from the outer end of the handle, the inner end of the bar 27 being bent laterally and passed through a longitudinal slot in the handle lever and constituting a pawl member 28 selectively engageable in recesses of a rack segment 29 secured 60 65 to the rear face of the cross piece 9, the pawl member being resiliently urged to engaging position by a coil spring 30 disposed in the inner portion of the bar of the handle member. It is noted that the crank arm 23

and link 21^a are disposed directly under the cross pieces 9 and are hence in such position as not to interfere with the proper upholstering and cushioning of the seat back structure, and these parts are concealed in the finished 70 condition of the chair by the usual rear covering (not shown) of the back structure.

The sliding movement effected in adjustment of the seat structure is shielded in the present structure by angle plates 31 extending about the intermediate portions of the rear legs and having their ends secured respectively to the side sills 7 and the rear sill 6, said angle plates also forming a stationary corner structure for the seat box and 80 serving to brace the general structure, arms 32 extending upwardly from the plates for securement to the lower ends of the rear posts 8 to provide additional bracing means.

I have thus provided a fairly simple structure which may be readily incorporated in the construction of a chair of the type herein shown, and of other types of chairs, and which provides for a ready adjustment of the inclination of the seat member of the 90 chair to meet the requirements of the user, by simply rocking the handle lever 26, the pawl of said lever being released by simply depressing the plunger 27 with the finger of the hand which grasps the lever. It is 95 noted that the spring 27 counterbalances the weight of the seat member from the lever mechanism when procuring the desired adjustment. It will further be appreciated that while I have shown lever connections 100 for adjusting the legs 17, the same results might be accomplished by permitting the legs to slide freely within the frame and using a bolt and wing lock to lock them in 105 desired or adjusted position.

While I have shown and described a preferred embodiment of my invention, it will be appreciated that various changes and modifications of structure and arrangement may be employed to meet differing conditions of use and manufacture without departing in any manner from the spirit of my invention.

What is claimed is:

1. A chair comprising a seat member, support legs for said seat member movable relative thereto, a pair of levers pivotally connected with the seat member and engaging said support legs, a common control lever, link means connecting said common control lever and said pair of levers and means for holding said common control lever against movement.

2. A chair comprising a seat member including a frame, triangular corner braces in 1 said frame provided with recesses, front legs having their upper end portions reduced and extending into the recesses and having slight lateral movement therein, the reduction of said front legs forming intermediate 1

shoulders engageable with the seat frame, rear legs having slidable engagement with the seat member and means for adjustably holding said rear legs against sliding movement.

3. A chair including a seat frame having its rear corner portions cut away, front legs connected with the forward corner portions of the seat frame, rear legs having their intermediate portions slidable in the cut away rear corner portions of the frame, angular

shield plates disposed about the cut away portions of the frame and rigidly secured to the frame and means for adjustably holding said frame and rear legs against relative movement.

In testimony that I claim the foregoing I have hereunto set my hand at Oshkosh, in the county of Winnebago and State of Wisconsin.

OSCAR H. SCHRAM.
